UNITED STATES PATENT OFFICE.

FREDERICK J. RAVLIN AND JOHN LOFGREN, OF CHICAGO, ILLINOIS.

PLUG-SWITCH.

1,169,426.

Specification of Letters Patent. Patented Jan. 25, 1916.

Application filed December 3, 1914. Serial No. 875,276.

To all whom it may concern:

Be it known that we, FREDERICK J. RAVLIN and JOHN LOFGREN, citizens of the United States, residing at Chicago, in the county of Cook and State of Illinois, have invented certain new and useful Improvements in Plug-Switches, of which the following is a specification.

Our invention relates to improvements in plug switches, and in some of its features more particularly to plug switches for three wire circuits, particularly adapted for three-phase wiring systems.

Among the general objects of our invention is to provide a weather proof switch socket construction that is simple, durable, efficient, easily installed and well adapted for installation in places where the switch is liable to receive rough usage.

20 In the drawing.

Figure 1 is a side elevation of the switch complete, showing its socket and plug members; Fig. 2 is a vertical section on line 2—2 of Figs. 1 and 4. Fig. 3 is a plan view of the socket construction; Fig. 4 is a vertical cross section on line 4—4 of Fig. 3, including a section of the plug; Fig. 5 is a cross section on line 5—5 of Fig. 4 and Fig. 6 is a cross section, through the plug on line 6—6 of Fig. 4.

In the drawings 10 indicates in general a socket or receptacle member and 11 a coöperating plug member.

12 indicates a conduit, of metal or other rigid material with respect to which the switch is to be located.

The socket 10 comprises a receptacle or casing 13, of metal, having a lower body portion 14 and an overlapping head 15 into which the body telescopes. The body part 14 is shaped to provide an odd number, say 3, of radiating chambers 16, the side and back walls of each forming substantially three sides of a rectangle and meeting on vertical junction lines 17, so that the several sections form a star, or radiating-chamber socket. The top of this body section is open, but its bottom is partially closed by a wall 18 that has therein a "star" opening 19 shaped similarly to, but larger than, a cross section of the plug 11, shown in Fig. 5, there being preferably formed in the juncture of two of the radiating lobes of the opening 19 a finger 20 that is adapted to fit in and co-operate with the slot 21 in the plug 11 so that the plug must always be fitted one way

with respect to the plural chambers of the sockets. Two of the corners of the receptacle body are provided with ears 22, having their back surfaces lying in a common plane 60 so that they may receive screws 23 or other fastenings to attach this body portion to a support. Within said body receptacle I provide a multiple piece insulating base 25, composed of sections 26 that may be duplicates 65 of each other, meeting at their edges on lines 27 that are continuations of the junction line 17 of the casing body and each recessed as at 28, along its inward face from its lower edge to a top wall portion 29, so that jointly such 70 structures may provide a three-chambered star socket. In height, the insulating base preferably extends from the bottom 18 of the casing body to a point somewhat above its upper edge. Each insulating base section 75 has mounted on the rear wall of its recess a contact spring 32, suitably anchored at its lower end so that its free end may project upwardly in the recess, the anchored end of said spring being suitably connected as by a 80 binding screw 33 or otherwise, with a metallic plate 34 that lies in a recess 35 made exteriorly in said back wall of the base section, so that an appropriate wire may readily be connected to the spring member 32. To receive such wiring a groove 36 is made exteriorly in the back wall of the section leading from its top to the recess 35. In order to prevent possibility of short circuiting the metallic structures appurtenant to the recess 35 upon the metal shell member 14 an insulating block 37 is preferably riveted or otherwise secured to the back wall of each chamber 16 of the casing body.

The head structure 15 of the casing provides a skirt 40 to interfit neatly around the radiating chambers 14 of the body member, and may be secured thereto (mainly for purposes of shipment) as by one or more screws 41. The head is closed at its top in a dome 42 in size approximating the circle that may be inscribed within the intersections 17 of the body chambers, and from the dome to the centers of the extensions that overlie the body chambers 16 there are run downwardly and outwardly curving ribs 43, the side walls of which diverge as they descend and merge into the flaring side walls of the dome, and at their bases meet the shoulder-forming horizontal wall portions 44 of the head. These head walls may all be of substantially uniform thickness, and it will be apparent

that interiorly the arched ribs 43 afford adequate wiring spaces leading from the central dome over the wire channels 36 of the several insulating base sections, while the wall portions 44 form shoulders that overlie and preferably bear upon the respective insulating base sections, thereby so snugly ensconcing insulating base sections in the receptacle that they are held by contact and friction against displacement in any direction when the casing parts are assembled, although each insulating base section is free from any extraneous connection with the casing that would prevent its ready removal when the casing parts are disassembled. Ears 46 are preferably cast integral with the skirt 40 and extend upward so that their screw-receiving orifices for the attaching screws 48 may be above the level of the contiguous parts, for convenient access, and it will be apparent that when both the body and head members of the casing are connected to a support they are very firmly related to each other and are not liable to become separated or displaced under the rough usage which is often attendant upon the forcing of the plug into the socket.

The head 15 is so related to the fixed conduit 12 that it may, upon occasion, be slipped up upon the conduit, to be out of the way. To this end, the extremity of the conduit is externally screw threaded as at 12'; the dome of the head member 15 has made therein a larger orifice 49, and a bushing 50 is provided, having an external bearing annulus 51 to receive the dome and a stem 52 that passes through the dome opening 49, this bushing being internally screw threaded for engagement with the threads 12'. Externally, also, the stem 52 is threaded and a nut 53 is screwed down theron to engage the top surface of the dome and make tight connection therewith.

It will be seen that in assembling the structure upon a conduit having a threaded end, and wiring the several switch-leaves 32 to the respective wires brought in through the conduit 12, the bushing 50 may be screwed into place, then the nut 53 unscrewed and, together with the head 15, slipped up onto the conduit out of the way. The several insulating base sections are then pulled out of their respective pockets and connected to the several electric wires that have been led in and snipped off to approximately the proper length. Then the wired base members are assembled in the body section 14, after which the head member 15 is brought back to position and secured to its support and then the body member 14 telescoped thereinto and in turn secured to its support. Of course this facility for easy separation of parts and the utilization of duplicate parts in the sectional construction of the insulating base, gives to the ap-

pliance a susceptibility to easy repair and inspection that is very desirable.

The plug 11 employed in connection with the socket may be of any desired material, preferably wood, having on each of its three lobes or leaves 59 a contact plate 60 secured by screws 61 each taking into a bushing 62 that is inserted through a hole bored from the opposite angle. The plates have binding screws 63 in recessed portions 64, and to these the plug wires are led through conduits 65 in the handle.

Having described our invention, what we claim is:

1. In a plug switch, the combination of a casing providing a number of radiating chambers more than two, an insulating base mounted therein and retained in position by contact with the casing, having a like number of recesses jointly forming a socket, contacts on the back walls of said recesses, and a plug providing a like number of radiating wings, and cooperating contacts on the appropriate faces of said wings. 85

2. A three wire plug switch receptacle 90 comprising more than two insulating base sections radially disposed, recessed from one end along their confronting faces, and meeting at their adjoining edges, a receptacle casing providing a similar plurality of radiating chambers respectively receiving and holding against radial and downward displacement the said base sections, a head member telescopically interfittting with said casing body and affording end bearings for 100 the upper ends of said base sections, said head member having a wiring orifice, and said base sections respectively carrying contact springs upon their inwardly facing back walls. 105

3. In a structure of the character described the combination of a two piece receptacle casing having its upper and lower sections telescopically interfitted, an insulating base therein having an end opening 110 socket, the upper casing having therein a wiring orifice, and means to connect the upper casing member with a conduit, said means comprising a stem, externally and internally threaded, projecting through said orifice and flanged below the top of the casing, and a nut on the threaded stem above the casing. 115

4. In a structure of the character described the combination of a two piece receptacle casing having its upper and lower sections telescopically interfitted, insulating base sections arranged within and positioned by contact with said casing sections, said base sections having recesses in their confronting faces jointly to form a socket and being endwise removable from the lower casing section when said casing sections are separated, the upper casing having therein a wiring orifice, and means to connect the upper casing member with a conduit, said 130

means comprising a stem, externally and internally threaded, projecting through said orifice and flanged below the top of the casing, and a nut on the threaded stem above the casing.

5 5. A three wire plug switch comprising a shell having a three-lobed star opening, with a projection 20; a three-chambered socket base having a contact in each chamber, and

a three-lobed plug, having a groove 21, and 10 bearing a contact on each lobe. In testimony whereof we hereunto set our hands:

FREDERICK J. RAVLIN.
JOHN LOFGREN.
